CLAIM

The ornamental design for a housing for an electronic device, as shown and described.

DESCRIPTION

FIG. 1 is a perspective view of a housing for an electronic device showing our new design;

FIG. 2 is a front view thereof;

FIG. 3 is a right view thereof;

FIG. 4 is a left view thereof; and,

FIG. 5 is a top view thereof.

The broken line showing of the connection terminal and cabling on the bottom of the housing, including the unshaded areas within the broken line showing, are for illustrative purposes only and form no part of the claimed design.
